UNITED STATES PATENT OFFICE.

HOWARD S. HIPWELL, OF READING, PENNSYLVANIA.

GAS-COCK.

993,372.

Specification of Letters Patent. Patented May 30, 1911.

Application filed April 15, 1910. Serial No. 555,719.

To all whom it may concern:

Be it known that I, HOWARD S. HIPWELL, a citizen of the United States, and a resident of the city of Reading, in the county 5 of Berks and State of Pennsylvania, have invented certain new and useful Improvements in Gas-Cocks, of which the following is a specification.

My invention relates particularly to gas 10 cocks, and has for its object the provision of improved means for insuring against such careless or accidental operation thereof as frequently endangers life.

The invention is fully described in connection 15 with the accompanying drawings and the novel features are clearly specified in the claims.

Figure 1 is a side elevation of a gas cock device embodying my complete invention, 20 all the parts being represented in the normal closed position. Fig. 2 is a plan view corresponding with Fig. 1, and Fig. 3 is a similar view showing the main valve opened. Figs. 4 and 5 are separate views 25 of the supplemental safety valve and the attachments thereto for its coöperative connection to the main valve.

The stop cock body 2 is formed with a burner tube 3 and is adapted for the reception 30 of a turn-plug valve 4 as usual. In my complete device as shown, a second stop cock body 2^a is formed in connection with the main body 2, and receives a supplemental or safety turn-plug valve 4^a which coöperates 35 with the main valve 4 in controlling the flow of gas to the burner, by means of connecting mechanism as hereafter described, so as to most effectually safeguard against escape of gas; the main valve 4 however be- 40 ing provided with means for automatically locking it in closed position which may be very advantageously employed independ- 45 ently of the additional safety valve 4^a though most completely utilized in connec- tion with the latter as shown. This auto- 50 matic locking means for the turn-plug valve 4 comprises a sheet-metal latch device 10 which is pivoted at a point 11 near the base of the body 2, and has an end portion 12 adapted to normally bear upon a seat or 55 shelf 13 formed on the body 2 while its lower edge portion 14 depends below said body. When the flattened finger-end 15 of the turn-plug valve 4 is turned from the open position indicated in Fig. 3 into the closed position indicated in Figs. 1 and 2,

the latch is raised thereby from its support- 60 ing seat 13, until the valve strikes the stop 16 provided as usual on the cock body, when the latch automatically falls into lock- 65 ing position as shown in Fig. 1, so as to posi- 70 tively prevent accidental opening of the valve. When however the operator takes hold of the finger-end 15 for the purpose of opening the valve, his finger naturally comes 75 into contact with the depending edge por- 80 tion 14 of the latch so as to raise the same and free the valve for the desired opening movement. In order to most effectively uti- 85 lize the supplemental valve 4^a as a further 90 safe guard, I provide for coöperatively connecting said valves so as to simultane- 95 ously effect the closing and locking of both valves, and for positively retaining the sup- 100 plemental valve in closed position until the main valve is first opened. To accomplish this I provide the valve 4, as shown, with a fixed crank arm 20, which is pivotally connected by a link 21 to a rock-arm 22 loosely mounted on the end of the supplemental 105 valve 4^a; said supplemental valve being also provided with a fixed arm 23, which is so set as to cause the depending pivot-pin 24 of the rock-arm 22 to engage said fixed arm 23 during the closing movement of the main 110 valve, and thereby cause the valve 4^a to be simultaneously turned to closed position. When thus set, the main valve 4 is locked by the latch 10 as already described, while the supplemental valve 4^a is prevented from turning in the normal direction by the connecting link 21, and in the reverse direc- 115 tion by an ordinary stop 25 on the cock body 2^a. After the main valve 4 is opened, as indicated in Figs. 1 and 2, the supple- 120 mental valve 4^a may be separately opened to permit a flow of gas to the burner, but when the main valve is closed the supple- 125 mental valve is automatically closed with it, and also locked by the main valve against 130 accidental turning.

What I claim is:—

1. In a gas-cock having a turn-plug valve with a flat finger-end; a cock body provided with a closure-stop for said valve, a latch-pivoting ear, and a latch-supporting seat; and a latch pivoted to said ear and having its free end supported on said seat and a depending portion adapted to normally en- 140 gage said finger-end when the valve is in 145 closed position.
2. A double stop-cock device comprising

a main turn-plug valve, a supplemental turn-plug valve, crank arms fixed to the respective valves, a rock-arm coaxial with said supplemental valve and adapted to operatively engage or disengage the crank arm thereon, and a link connecting the main valve crank arm and said rock-arm.

In testimony whereof, I affix my signature, in the presence of two witnesses.

HOWARD S. HIPWELL.
